UNITED STATES PATENT OFFICE

EDWARD T. BIRDSALL, OF CLEVELAND, OHIO, ASSIGNOR TO CHARLES H. BUTLER, OF OAKLAND, CALIFORNIA

STREET-CLEANING MACHINE

Application filed March 6, 1926. Serial No. 92,668.

This invention relates to street cleaning machines, and more particularly to machines of the pneumatic or vacuum type which are propelled along the streets and which, as they travel therealong, sweep up the refuse, collect the dust and lighter particles by vacuum means, separate the dust and lighter particles of refuse from the air, discharge the cleansed air into the atmosphere, and collect both the heavy and light refuse into receptacles or hoppers. Such a machine forms the subject matter of Patents Nos. 808,006, 880,124 and 909,865 granted to Charles H. Butler, and the object of this invention is to provide an improvement in such machines, such improvement residing particularly in means for conveniently shaking the dust collecting tubes to drop the dust collected thereon.

In the accompanying drawing I have shown one specific embodiment of my invention, but it will be understood that the invention can be otherwise embodied and that the drawing is not to be construed as defining or limiting the scope of the invention, the claims appended to this specification being relied upon for that purpose.

Referring to the figures of the drawing:

Figure 1 is a side elevation, partially in section, showing a street cleaning machine embodying my invention.

Figure 2 is a plan sectional view taken on line II—II of Fig. 1.

The machine shown in Fig. 1 is a self-propelled street cleaning machine having a sweeping broom 1 and mechanism within the body 2 for receiving the refuse and carrying the same to containers therein. The fine particles of dust are carried upwardly in the direction of the arrows by a blower on a shaft 3. This draught of air carries the dust into a chamber 4. From thence the air passes into dust collecting tubes 5 and outwardly through the tubes and out of the body 2 through slots beneath louvers at 6. Both ends of the tubes 5 are open to the chamber 4, but the chamber surrounding the tubes is separated from the chamber 4 by partitions 7 and 8 supporting the ends of the tubes.

The tubes 5 consist of thin closely woven cloth which will allow the air to pass out-

wardly through the meshes thereof, but which will retain the finest dust within the tubes. The tubes may be mounted in any desired manner. A dust receiving hopper 9 is located beneath the tubes. A considerable portion of the dust will cling to the tubes instead of dropping into the hopper and my invention herein provides means convenient to the operator for shaking the tubes to dislodge this dust.

A pair of rods 10 extend longitudinally through the tube chamber and are provided with transversely extending bars 11 thereon between the adjacent rows of tubes. The rods are movably supported by links 12 within the tube chamber. The forward ends of the rods extend through the front wall of the housing and are provided with an operating handle 13 thereon, adjacent the driver's seat. The construction is such that the driver can grasp the handle 13 and rapidly reciprocate the rods longitudinally in a manner shaking the tubes and causing the clinging dust to drop therefrom into the hopper.

Having thus described my invention, what I claim is:

In combination with a dust chamber, a dust-collector comprising a plurality of relatively spaced downwardly extending dust settling tubes communicating at opposite ends with the chamber and through which the dust laden air is directed from the dust chamber, the spaces between the tubes intermediate the opposite ends thereof being separated from the dust chamber and being provided with outlet openings whereby the dust laden air will pass into the tubes through the walls of the tubes and out of the outlet openings, a rack extending longitudinally and transversely between the tubes in a position adapted to come into contact with all of the tubes upon longitudinal movement of the rack, said rack being loosely suspended and capable of operation to shake the tubes in a manner dislodging the dust collected therein.

EDWARD T. BIRDSALL.
